REGISTER OR AIR DIFFUSER

Richard James Wallerstedt, Dowagiac, Mich., assignor to
Premier Furnace Company, Dowagiac, Mich.

Application February 18, 1957; Serial No. 640,637

12 Claims. (Cl. 98—40)

This invention relates to air registers or diffusers of the type quite commonly designated as baseboard diffusers.

The main objects of the invention are:

First, to provide an air register or diffuser which may be very economically produced, at the same time is efficient and attractive in appearance and may be quickly installed and is adaptable to widely varying use conditions.

Second, to provide a register or diffuser of this type provided with a damper for regulating the flow or discharge which in all positions of adjustment serves as a baffle for effectively distributing the air throughout the length of the register.

Third, to provide a register or diffuser structure having these advantages which includes a detachable front panel on which the damper mechanism is mounted to constitute a unit and greatly facilitating the assembly of the parts and the installation thereof.

Objects relating to details and economies of the invention will appear from the description to follow. The invention is defined and pointed out in the claims.

A preferred embodiment of the invention is illustrated in the accompanying drawing, in which:

Fig. 1 is a fragmentary front perspective view of a register embodying my invention, the relation of the register to a floor and wall being conventionally illustrated.

Fig. 2 is an enlarged transverse vertical section on a line corresponding to broken line 2—2 of Fig. 3.

Fig. 3 is a fragmentary view in longitudinal section on a line corresponding to broken line 3—3 of Fig. 2.

Fig. 4 is a fragmentary front elevational view illustrating the details of the damper operating mechanism.

Fig. 5 is a fragmentary front elevational view of the register with parts broken away to further illustrate the damper and its operating mechanism.

Fig. 6 is a fragmentary view in section on a line corresponding to line 6—6 of Fig. 4.

Fig. 7 is a fragmentary view of the inside of the front plate and damper and operating mechanism.

Fig. 8 is a perspective view of the front panel and damper as an assembled unit.

Fig. 9 is a fragmentary rear perspective view of certain of the parts shown in Figs. 2 and 8.

Fig. 10 is a perspective view of the damper operating lever support and stop member.

In the accompanying drawing 1 represents a floor, and 2 a wall.

The register or diffuser of the embodiment of my invention illustrated comprises a rear wall member 3, top wall member 4, bottom wall member 5 and front wall member 6. These parts are desirably formed of a strip of sheet metal stock folded longitudinally.

In the embodiment illustrated the front wall member 6 is rearwardly inclined and is of substantially less height than the rear wall member 3. The top wall member 4 is of substantially less width than the bottom wall member 5 and, in the embodiment illustrated, terminates in an angled downwardly projecting flange 7.

2

The end walls 8 have inturned border flanges 9 which are fittingly received within the rear, bottom, front and top wall members and are secured thereto by screws, rivets or spot welding, the securing means not being illustrated.

The end walls 8 have V shaped recesses 10 positioned at the front edge of the top wall member. The bottom wall is provided with an opening 11 therein adapted to receive a flue or delivery pipe as is conventionally illustrated at 12.

The bottom is provided with adjustable sections 13 slidably mounted thereon and adapted to be adjusted to close that portion of the bottom or inlet opening not occupied by the inlet flue. Desirably a pair of these members 13 are provided so that the register may be variably positioned relative to the inlet flue which, of necessity, must be positioned in regard to structural requirements of the room or building. When the register has been positioned relative to the inlet flue and the members 13 properly adjusted they are secured in their adjusted positions by means of the screws, indicated at 14. These screws also serve to secure the register in its adjusted position as the screws pass through the bottom wall member.

The front panel 15 is complementary to the front wall member 6 and its lower edge is arranged in overlapping relation to the upper edge thereof. The panel 15 is provided with supports 16 disposed on the inner side of the wall member 6. The panel 15 is detachably secured to the end wall members by means of screws 17 and the aforesaid supported engagement of the lower edge of the panel with the front wall member 6.

The upper edge 18 of the front panel is spaced from the front edge of the top wall to provide an elongated slot-like discharge opening. At its upper edge the panel 15 is provided with an inturned downturned projecting flange like extension 19 which terminates at its lower edge in a forwardly directed lip-like damper hinge element 20.

The damper 21 is provided with a rearwardly projecting lip-like hinge element 22 on its upper edge, which is in hinging engagement with the hinge element 20. This supports the damper to swing between the front and rear walls, its open position being illustrated in full lines in Fig. 2 and its closed position by dotted lines.

The angled damper actuating lever designated by the numeral 23 is pivotally mounted on the pivot 24 which in the embodiment illustrated is in the form of a bolt disposed through the front panel and the downturned flange 19 thereof and serves the double purpose of a pivot and also to hold the flange in position to effectively support the damper and prevent the disengagement of its hinge element 22 from the hinge element 20 on the front panel.

One arm of the damper adjusting lever constitutes a finger piece 25 which projects above the front panel for convenience in manipulation and the other arm 26 is notched at 27 to engage the rearwardly projecting ear 28 mounted on the rear side of the damper. The stop member 29 is also mounted on the pivot bolt 24 and is provided with an adjustable stop 30 coacting with the stop extension 31 of the adjusting lever to limit the opening movement of the damper and with the stop 32 to limit the closing movement thereof. The outwardly turned stop 32 has a prong 321 on its outer end which engages in a hole 322 (see Fig. 7) provided therefor in the downwardly turned flap 19 of the front panel. The prong 321 together with the pivot 24 prevent the stop member 29 from rotating so that the adjustable open stop 30 and the non-adjustable close stop 32 are fixed relative to the front panel.

The damper depends within the register in overhanging relation to the inlet and in all positions of adjustment of the damper it serves as a baffle to deflect or

distribute the air entering the register through the inlet throughout the length of the register.

In the preferred embodiment illustrated the damper is of angled section comprising a forwardly inclined upper position 33, that is, it is inclined relative to the intermediate portion 34 and a rearwardly inclined lower portion or section 35 which is rearwardly inclined relative to the intermediate section and terminates in a longitudinal flange 36 which closes against the rear wall when the damper is in fully closed position as indicated by dotted lines in Fig. 2.

With this arrangement of parts the damper and its operating mechanism may be assembled on the front panel to constitute a unit therewith and the front panel readily installed on the wall unit.

This arrangement not only enables the economical manufacture of the parts but also enables rapid installation of the register and positioning relative to the inlet flue. The screws 14 for securing the members 13 also serve to secure the register in its proper installation to the floor and wall. The front panel with the damper parts assembled thereon are quickly installed and may be very quickly and easily removed should occasion require.

I have illustrated and described my invention in a highly practical embodiment thereof. I have not attempted to illustrate various possible modifications which I contemplate as it is believed this disclosure will enable those skilled in the art to embody or adapt the invention as may be desired.

Having thus described the invention, what is claimed as new and is desired to be secured by Letters Patent is:

1. An elongated air register comprising integral rear, top, bottom and front wall members, the top member being of substantially less width than the bottom member and having a downwardly projecting rearwardly facing angled flange on its forward edge, the front wall member being rearwardly inclined and of substantially less height than the rear wall member, end walls secured to said wall members, the upper ends of said end walls having V-notches therein, a front wall panel disposed with its lower edge in overlapping detachable engagement with said front wall member and detachably secured to said end walls and having an inturned downwardly projecting flange on its upper edge terminating in a forwardly projecting lip constituting a hinge element, the upper edge of said front panel being spaced from the forward edge of said top wall and coacting therewith to define an elongated slot-like air discharge, one of said wall members having an inlet opening therein, a damper having a rearwardly projecting lip on its upper edge constituting a hinge element hingedly engaged with said hinge element of said front wall panel, and a damper actuating lever pivotally mounted on said downwardly projecting flange of said front wall panel with one end thereof projecting therefrom and constituting a finger piece, said damper having a rearwardly projecting arm engaged with the other end of said actuating lever.

2. An elongated air register comprising integral rear, top, bottom and front wall members, the top member being of substantially less width than the bottom member, the front wall member being rearwardly inclined and of substantially less height than the rear wall member, end walls secured to said wall members, a front wall panel disposed with its lower edge in overlapping detachable engagement with said front wall member and detachably secured to said end walls and having an inturned downwardly projecting flange on its upper edge terminating in a forwardly projecting lip constituting a hinge element, the upper edge of said front panel being spaced from the forward edge of said top wall and coacting therewith to define an elongated slot-like air discharge, one of said wall members having an inlet opening therein, a damper having a rearwardly projecting lip on its upper edge constituting a hinge element hingedly engaged with said hinge element of said front wall panel, and a damper ac-

tuating lever pivotally mounted on said downwardly projecting flange of said front wall panel with one end thereof projecting therefrom and constituting a finger piece, said damper having a rearwardly projecting arm engaged with the other end of said actuating lever.

3. An elongated air register comprising rear, top, bottom, and end wall members, the top wall member being of substantially less width than the bottom wall, a front wall panel detachably secured to said end walls and having an inturned downwardly projecting extension on its upper edge provided with a forwardly projecting hinge element, the upper edge of said front panel being spaced from the forward edge of said top wall and coacting therewith to define an elongated slot-like air discharge opening for said register, one wall member having an inlet opening therein, a damper having a rearwardly projecting hinge element on its upper edge hingedly engaged with said hinge element of said front wall panel, and a damper actuating lever mounted on said downwardly projecting extension of said front wall panel and operatively connected to said damper, said damper swingably depending between said front panel and said rear wall and being of angled cross section including a forwardly inclined upper section terminating in said hinge element of said damper, an intermediate section, and a lower section inclined rearwardly relative to said intermediate section.

15 4. An elongated air register comprising rear, top, bottom, and end wall members, the top wall member being of substantially less width than the bottom wall, a front wall panel detachably secured to said end walls and having an inturned downwardly projecting extension on its upper edge provided with a forwardly projecting hinge element, the upper edge of said front panel being spaced from the forward edge of said top wall and coacting therewith to define an elongated slot-like air discharge opening for said register, one wall member having an inlet opening therein, a damper having a rearwardly projecting hinge element on its upper edge hingedly engaged with said hinge element of said front wall panel, and a damper actuating lever mounted on said downwardly projecting extension of said front wall panel and operatively connected to said damper, said damper swingably depending between said front panel and said rear wall and being of angled cross section including a forwardly inclined upper section terminating in said hinge element of said damper, an intermediate section, and a lower section inclined rearwardly relative to said intermediate section.

20 5. An elongated air register comprising rear, top, bottom, and end wall members, the top wall member being of substantially less width than the bottom wall, a front wall panel detachably secured to said end walls and having an inturned downwardly projecting extension on its upper edge provided with a forwardly projecting hinge element, the upper edge of said front panel being spaced from the forward edge of said top wall and coacting therewith to define an elongated slot-like air discharge opening for said register, one wall member having an inlet opening therein, a damper having a rearwardly projecting hinge element on its upper edge hingedly engaged with said hinge element of said front wall panel, and a damper actuating lever mounted on said downwardly projecting extension of said front wall panel and operatively connected to said damper, said damper swingably depending between said front panel and said rear wall.

25 6. An elongated air register comprising rear, top, bottom, front and end wall members constituting a unitary assembly, a rearwardly inclined front wall panel detachably secured to said assembly and disposed with its upper edge in spaced relation to the forward edge of said top wall and coacting therewith to define an elongated air discharge opening for the register, the bottom wall member having an air inlet opening therein, a damper extending lengthwise of and hingedly mounted at its upper edge on the inner side of said front wall panel to depend downwardly at the inner side thereof and with its lower edge above the inlet, the upper edge of said damper being closely adjacent to said front wall panel and below said discharge opening, said damper constituting a baffle positioned between said inlet and discharge in all positions of adjustment other than its fully closed position, said damper being of angled cross section and including a forwardly inclined upper section, an intermediate section and a lower section rearwardly inclined relative to said intermediate section and terminating in a rearwardly projecting flange engageable with the rear wall member when the damper is fully closed, stops limiting the opening and closing movement of the damper, the opening movement stop being adjustable, the lower end of the damper being in spaced relation to the front wall panel when engaged with said open position stop, and means for adjusting said damper on said front wall panel.

30 7. An elongated air register comprising rear, top, bottom, front and end wall members, a front wall panel disposed with its upper edge in spaced relation to the forward edge of said top wall and coacting therewith to define an elongated air discharge opening for the register,

the bottom wall member having an air inlet opening therein, a damper extending lengthwise of and hingedly mounted at its upper edge on the inner side of said front wall panel to depend downwardly at the inner side thereof and with its lower edge above the inlet, the upper edge of said damper being closely adjacent to said front wall panel and below said discharge opening, said damper constituting a baffle positioned between said inlet opening and said discharge opening in all positions of adjustment other than its fully closed position, said damper being of angled cross section and including a forwardly inclined upper section, an intermediate section and a lower section rearwardly inclined relative to said intermediate section and terminating in a rearwardly projecting flange engageable with the rear wall member when the damper is fully closed, and means for adjusting said damper on said front wall panel.

7. An elongated air register comprising rear, top, bottom, front and end wall members, a front wall panel disposed with its upper edge in spaced relation to the forward edge of said top wall and coacting therewith to define an elongated air discharge opening for the register, the bottom wall member having an air inlet opening therein, a damper extending lengthwise of and hingedly mounted at its upper edge on the inner side of said front wall panel to depend downwardly at the inner side thereof and with its upper edge below said discharge opening and its lower edge above the inlet opening, the upper edge of said damper being closely adjacent to said front wall panel preventing substantial circulation between the front panel and the damper, said damper constituting a baffle in all positions of adjustment other than its fully closed position, and means for adjusting said damper on said front wall panel.

8. An elongated air register comprising bottom, rear, front, end and top wall members, the top wall member projecting forwardly from the rear wall and terminating in spaced relation to the upper edge of the front wall and coacting therewith to define an elongated discharge opening for the register extending longitudinally from end to end thereof, said front wall having an inturned downwardly projecting extension on its upper edge provided with a hinge element at its lower edge disposed in a plane below said discharge opening, a damper having a hinge member on its upper edge hingedly engaged with said hinge element on said front wall member and swingably depending therefrom for swinging adjustment between the front and rear walls, one of said wall members having an air inlet opening disposed in a plane substantially spaced below the swinging edge of said damper in all positions of adjustment thereof, the damper in its fully open position being substantially spaced from the front wall and from said air inlet opening and constituting in that position a distributing baffle for the incoming air, and manually operated means for variably positioning said damper on its said hinge element and supporting it in adjusted position.

9. An elongated air register comprising bottom, rear, front, end and top wall members, the top wall member projecting forwardly from the rear wall and terminating in spaced relation to the upper edge of the front wall and coacting therewith to define an elongated discharge opening for the register extending longitudinally from end to end thereof, said front wall having an inturned downwardly projecting extension on its upper edge provided with a hinge element at its lower edge disposed in a plane below said discharge opening, a damper having a hinge member on its upper edge hingedly engaged with

said hinge element on said front wall member and swingably depending therefrom for swinging adjustment between the front and rear walls, one of said wall members having an air inlet opening disposed in a plane substantially spaced below the swinging edge of said damper in all positions of adjustment thereof, and manually operated means for variably positioning said damper on its said hinge element and supporting it in adjusted position.

10. An elongated air register comprising bottom, rear, front, end and top wall members, the top wall projecting forwardly from the rear wall, and the forward edge thereof toward the upper edge of the front wall and coacting therewith to define an elongated discharge opening for the register, said front wall having a hinge element on its inner side disposed in a plane below said discharge opening, a damper having a hinge member on its upper edge coacting with said hinge element on said front wall member and swingably depending therefrom for swinging adjustment between the front and rear walls, there being an air inlet opening to said housing disposed in a plane substantially spaced below the swinging edge of said damper in all positions of adjustment thereof, said damper in its fully open position being substantially spaced from the front wall and from said air inlet opening and constituting in that position a distributing baffle for the incoming air, and manually operated means for variably positioning said damper on its said hinge element and supporting it in adjusted position.

11. An elongated air register comprising bottom, rear, front, end and top wall members, the top wall projecting forwardly from the rear wall and the forward edge thereof toward the upper edge of the front wall and coacting therewith to define an elongated discharge opening for the register, said front wall having a hinge element on its inner side disposed in a plane below said discharge opening, a damper having a hinge member on its upper edge coacting with said hinge element on said front wall member and swingably depending therefrom for swinging adjustment between the front and rear walls, there being an air inlet opening to said housing disposed in a plane substantially spaced below the swinging edge of said damper in all positions of adjustment thereof, and manually operated means for variably positioning said damper on its said hinge element and supporting it in adjusted position.

12. An elongated air register comprising bottom, rear, front and end wall members, and a top wall projecting forwardly from the rear wall member with its front edge in spaced relation to the top edge of the front wall and coacting therewith to define an elongated discharge opening for said register extending longitudinally thereof, said front wall member having an inturned downwardly projecting extension on its upper edge provided with a hinge element disposed in a plane below said discharge opening, and a damper extending from end to end of said discharge opening hingedly engaged with said hinge element on said front wall member and depending therefrom for swinging adjustment between said front and rear walls, one of said wall members having an air inlet opening disposed in a plane substantially below the swinging lower edge of the damper in all positions of adjustment thereof.
